UNITED STATES PATENT OFFICE.

HEINRICH BAUMEISTER, OF BERLIN-PANKOW, GERMANY, ASSIGNOR TO GENERAL ELECTRIC COMPANY, A CORPORATION OF NEW YORK.

ELECTRIC STARTING MOTOR FOR POWER ENGINES.

Application filed May 18, 1922. Serial No. 560,775.

To all whom it may concern:

Be it known that I, HEINRICH BAUMEISTER, a citizen of Germany, residing at Berlin-Pankow, Germany, have invented certain new and useful Improvements in Electric Starting Motors for Power Engines (for which I have filed an application in Germany January 6, 1920), of which the following is a specification.

10 This invention relates in general to a starting motor of the kind in which the motor and the wheel to be rotated by it are coupled with each other by means of a pinion that is adapted to be slewed around the 15 motor axle; in particular the invention relates to slewing the pinion by the rotary motion of the starting motor, viz by the mediation of a coupling which is temporarily elastic and couples the motor with the slew- 20 lever during the throwing-on period. The object proper of this arrangement is to obviate the special electromagnetic means hitherto employed for operating the slew- 25 means for the pinion in question.

30 In order to make my invention more clear, I refer to the accompanying drawing, in which similar letters denote similar parts throughout the several views, and in which Fig. 1 is a diagrammatical representation of the complete combination and arrangement of parts, the rotary parts being shown in axial direction. Fig. 2 is an axial section through these latter parts. Fig. 3 is an illustration similar to Fig. 2 showing a slightly modified form of construction. Fig. 4 is also an illustration similar to Fig. 2, or 3 respectively, and shows a third form of execution; this figure is drawn on a somewhat larger scale. Fig. 5 is an axial view of a 40 detail of Fig. 4.

45 Referring to Figs. 1 and 2, this is a form of construction in which the slewing of the coupling pinion is effected by the rotary motion of the motor through the mediation of an eddy-current coupling. *a* is the motor shaft, *b* a bearing cover, *r* a pinion keyed to said shaft, *s* an intermediate gear or coupling pinion which is rotatably supported on a lever *c* by means of a bolt and meshes with 50 the pinion *r*, and *t* a gear connected to a power engine. This lever *c* may be slewed around the motor axle and is subjected to the action of a spring *g* which tends to pull

the lever back into the throwing-in position. In Fig. 1 the lever *c* is shown as thrown on; 55 the cog-wheels *s* and *t* mesh with each other, and the arm *h* which is rigidly connected with the lever *c* bears against the abutment *i*. The slewable pinion *s*, after having been thrown on, is held fast in this position (Fig. 60 1) as long as the driving pinion *r* exerts a turning moment over the slewable pinion *s* upon the toothed rim *t*. To throw on the pinion *s* by the rotary motion of the starting motor, conformably with this invention, an 65 eddy-current coupling is provided which consists of a pole core *e* attached to the lever *c*, a magnet coil *f*, and a metal disk *d* which is affixed to the motor shaft and rotates in front of the core *e*. To throw on the eddy- 70 current coupling a current is made to pass through the coil *f* so that the disk *d* rotates in a strong magnetic field and exerts, re-acting, a turning moment upon the core *e* and the lever *c* by virtue of the eddy-currents induced in it. The lever is thus turned in the 75 same direction as the disk *d*, and the spring *g* is put under tension.

80 The succession of phases when throwing on the eddy-current coupling is as follows: When depressing the push-button 5 the current flows from the battery A over the contacts 2 and 1 which are bridged, in the position of rest of the gearing, by the contact lever *k*; then the current flows through the coil 85 *f*, the motor *M* and then back to the battery. This makes the motor *M* start at the same time the pole core *e* is excited so that it, together with the lever *c*, is taken along by the eddy-current turning moment existing between the rotating disk *d* and the pole core 90 *e*; the slewable pinion *s* and the toothed rim which is to be driven are thus made to mesh with each other.

95 After the slewable pinion *s* has been thrown into gear with the toothed rim *t*, the switching lever is in a position in which it bridges the contacts 4 and 3. From this moment the current flows directly from the battery to the motor *M* and drives this with 100 full power. Owing to the cog-wheel re-action now arising the lever is further turned until the arm *h* meets the bolt *i* and the teeth of the wheels *s* and *t* are completely in gear with each other. Simultaneously the 105 switching lever *k* leaves the segments 1 and

2 whereby the current through the magnet coil f is interrupted. The eddy-current coupling is now released and the motor may transmit its full power to the toothed rim t 5 to be driven. Disengagement of the pinion s and the toothed rim t from one another takes place only when the power engine begins to operate under its own power, whereupon the tooth-reaction ceases, or reverses 10 respectively, the lever c is released and the gears are thrown out of mesh by the spring g .

The above-described arrangement makes 15 use only of electromagnetic force for slew- ing the lever e , but it is as well possible to use mechanical friction in lieu of the electro- magnetic force whereby the effect may be in- creased. For that purpose nothing else is 20 necessary but to make the disk d axially displaceable and to use magnetic material for it so that it contacts with the core e when being attracted, by it and transmits the necessary turning moment to the lever 25 c by the friction between it and the core.

As the practical execution of the above- 30 described arrangement with its eddy-cur- rent coupling or friction coupling is con- nected with some difficulties, it is preferable to transmit the rotary motion of the motor armature to the slewing lever in some other manner, for instance by the means illus- 35 trated in Fig. 3. Here an auxiliary pinion u is made use of, which is in permanent gear with the pinion r and is revolutely supported by the lever c and exerts a turning moment upon it by impeding its rotary motion. The cog-wheel u is rotatably supported 40 upon the core e of a pot-shaped magnet n which is directly connected with the lever c and has a hopper-shaped rim into which fits a correspondingly shaped projection of the cog-wheel u . On exciting the coil f the cog-wheel u is so powerfully attracted that owing to the conical pressure surfaces at the 45 hopper-shaped rim of the magnet and the projection of the associate cog-wheel, a strong braking action arises whereby the lever c is slewed.

Anyhow, the magnetic pulling power re- 50 quired to produce the necessary friction is still pretty great, but this state of things may be improved by directly holding fast the pinion u by means of a pawl-like or claw-like coupling, perhaps of the kind 55 illustrated in Figs. 4 and 5, and by employing the magnet solely for actuating the pawl or claw. But as it is necessary to make provision for the case where the teeth of the 60 wheels s and t do not mesh with each other, the coupling between the lever and the motor shaft must have a certain elasticity, that is to say, an elastic connection between the cog-wheel u and the coupling or pawl 65 must be provided. Such an arrangement is illustrated in Figs. 4 and 5. The electro-

magnet n is also in this instance pot-shaped and its projecting core-portion is surrounded with a sleeve m , which carries the cog- wheel u and a coupling disk l . The elastic connection between the cog-wheel and the 70 disk is effected by a spring p , whereas a spring x presses the disk l outwards after it has been disengaged. On exciting the coil 75 f , the disk l is drawn against the pot n and suitably provided lugs of it engage cor- respondingly located recesses o of the pot rim whereby the disk is prevented from ro- 80 tating upon the bolt e . Also the cog-wheel which is elastically coupled with l by the spring p is held fast, whereby the desired turning moment upon the slewing lever is ex- 85 ereted. In case the gear wheels s and t fail to mesh the slewing of the lever is de- layed until, owing to the rotation of the cog-wheel u , in connection with the tension- 90 ing of the spring p , the wheel s meshes with the wheel t .

I claim:

1. In combination, an electric starting 90 motor for power engines, said motor having a shaft, a pinion on said motor shaft, an engine gear, an intermediate gear actuated by said pinion, a slewing lever for said intermediate gear, a member arranged for rotary motion, and an electromagnetic pawl 95 device elastically connected with said shaft for checking the rotary motion of said member and thereby coupling said motor shaft to said lever.

2. In combination an electric starting 100 motor for power engines said motor having a shaft, a pinion on said motor shaft, an engine gear, an intermediate gear actuated by said pinion, a slewing lever for said intermediate gear, an electromagnet for 105 coupling said motor shaft to said lever, and a contact in the circuit of said electromagnet controlled by said lever, said contact being closed before said lever is slewed to ener- 110 gize said motor and bring the intermediate gear into mesh with said engine gear and opened when said gears are in mesh.

3. In combination, an electric starting 115 motor for power engines, said motor having a shaft, a pinion on said motor shaft, an engine gear, an intermediate gear actuated by said pinion, a slewing lever for said intermediate gear, a member for rotating said 120 slewing lever, a gear elastically connected to said member, and an electromagnet for checking the rotary motion of said member and thereby coupling said motor shaft to said lever.

4. In combination, a source of power, 125 an electric starting motor for power en- gines, said motor having a shaft, a pinion on said motor shaft, an engine gear, an intermediate gear actuated by said motor, a slewing lever for said intermediate gear, an electromagnet for coupling said motor shaft 130

to said lever, a contact in the circuit of said electromagnet controlled by said lever, said contact being closed before said lever is slewed to energize said motor and bring the 5 intermediate gear into mesh with said engine gear, said contact being opened when said gears are in mesh, and a second contact adapted to be closed to directly connect said motor to said source when said intermediate gear is brought into mesh with 10 said engine gear.

In testimony whereroof I affix my signature.

HEINRICH BAUMEISTER.
